UNITED STATES PATENT OFFICE.

THEODORE M. CLARK, OF BOSTON, MASSACHUSETTS.

SELF-CLOSING ELEVATOR-DOOR.

SPECIFICATION forming part of Letters Patent No. 253,345, dated February 7, 1882.

Application filed November 1, 1881. (No-model.)

To all whom it may concern:

Be it known that I, THEODORE M. CLARK, of Boston, Suffolk county, Massachusetts, have invented a new and useful Improvement in 5 Self-Closing Elevator-Doors, of which the following is a full, clear, and exact description.

My invention relates to the doors of elevator-shafts, and has for its object to combine with self-closing doors automatically-acted devices for retaining each door open during the time the car or platform is stopped at such door.

The invention consists in combining a pivoted latch-bar and a bow-spring on the door-frame with a door having a stud and an elevator-platform having a lug, as hereinafter described.

Reference is to be had to the accompanying drawings, forming a part of this specification, 20 in which similar letters of reference indicate corresponding parts in all the figures.

Figure 1 is a sectional elevation, showing one side of a shaft with the door and elevator-platform provided with the improved devices. 25 Fig. 2 is a similar view, showing the latch in its normal position. Fig. 3 is a front elevation with the parts in the position of Fig. 1, and Fig. 4 shows the parts of the latch separately.

A is one side wall of the shaft, constructed 30 of either brick or wood, and provided with the usual door-opening.

B is the door, supported upon or suspended from a track which is slightly inclined, so that the door shall close by gravity when not held 35 open.

C is the elevator-platform.

At one side of the door-opening is a latch-bar, a, hung on a pivot, b, its inner end projecting into the shaft, and its outer end bent 40 or formed, as shown most clearly in Fig. 4, with a beveled flange, a', that extends between the wall and the door. On the inner side of the wall is a plate or strip, c, of spring metal, attached rigidly by one end and engaging by a 45 slot in its free end the inner end of latch a.

The spring c is retained in connection with the latch by an eye, d, and is of bow form, so that its middle portion extends into the shaft a sufficient distance for contact with a friction-roller, e, that is attached in a lug or projection 50 of the platform C. On the door is a pin or stud, f, in position for engaging the flange a' of the latch-bar when the latter is released.

The operation is as follows: In the normal position shown in Fig. 2 the latch-bar is retained upward by the spring c, and the door can be opened from the floor side, as is often desired. The door is pulled back before the latch is thrown into locked position, so that when the platform reaches the floor the spring 55 is flattened by friction-roll e, the latch tilted, and the stud f, located behind the latch end u', holds the door open. On an up or down movement of the elevator the spring is released, the latch tilted, and the door allowed 60 to be closed by gravity.

This device is simple and efficient. It allows the use of self-closing doors without its being necessary for the elevator attendant to hold them open.

It is evident that the details of construction can be somewhat different from those shown and described without departing from the spirit of my invention. An eccentric may be substituted for the spring for lifting the latch, 75 and the location and shape of the latch-bar varied as most convenient.

Having thus described my invention, I claim as new and desire to secure by Letters Patent—

The pivoted latch-bar a and bowed spring 80 c, combined with door B, having stud f, and platform C, having a lug or projection for contact with the spring, substantially as and for the purposes set forth.

THEODORE MINOT CLARK.
